UNITED STATES PATENT OFFICE.

CLAUDE G. PUTNAM, OF LOS ANGELES, CALIFORNIA, AND DICK WICK HALL, OF SALOME, ARIZONA.

DESIGN FOR AN INCENSE BURNER.

Application filed February 11, 1925. Serial No. 12,351. Term of patent 7 years.

To all whom it may concern:

Be it known that we, CLAUDE G. PUTNAM and DICK WICK HALL, citizens of the United States, and residents, respectively, of Los Angeles, Los Angeles County, California, and Salome, Yuma County, Arizona, have invented a new, original, and ornamental Design for Incense Burners, of which the following is a specification, reference being had to the accompanying drawings, forming a part thereof.

In the drawings, the figure is a perspective view of an incense burner, showing our new design.

We claim:

The ornamental design for an incense burner, substantially as shown.

CLAUDE G. PUTNAM.
DICK WICK HALL.
